CLAIM

The ornamental design for an adhesive tape dispenser, as shown.

DESCRIPTION

FIG. 1 is a perspective view of an adhesive tape dispenser in an open, dispensing position showing my new design;

FIG. 2 is a top view thereof;

FIG. 3 is a right side view thereof;

FIG. 4 is a left side view thereof;

FIG. 5 is a front view thereof;

FIG. 6 is a rear view thereof;

FIG. 7 is a bottom view thereof;

FIG. 8 is a perspective view thereof in a closed position;

FIG. 9 is a top view thereof in the closed position;

FIG. 10 is a right side thereof in the closed position;

FIG. 11 is a left side view thereof in the closed position;

FIG. 12 is a front view thereof in the closed position;

FIG. 13 is a rear view thereof in the closed position; and,

FIG. 14 is a bottom thereof in the closed position.
